(57) **CLAIM**

The ornamental design for an internally lighted jewelry display, as shown and described.

DESCRIPTION

FIG. 1 is a perspective partially-exploded view of an internally lighted jewelry display, showing my new design;

FIG. 2 is a front elevational view of the invention;

FIG. 3 is a rear elevational view of the invention;

FIG. 4 is a left-side elevational view of the invention, the right-side elevational view being a mirror image thereof;

FIG. 5 is a top plan view of the invention; and,

FIG. 6 is a bottom plan view of the invention.

The broken lines are for the illustrative purposes only and form no part of the claimed design.
